CLAIM

The ornamental design for a container carrier, as shown and described.

DESCRIPTION

FIG. 1 shows a top perspective view of a first embodiment of a container carrier showing our new design;
FIG. 2 shows an enlarged top perspective view thereof;
FIG. 3 shows a bottom perspective view thereof;
FIG. 4 shows an enlarged bottom perspective view thereof;
FIG. 5 shows a front elevation view thereof;
FIG. 6 shows a rear elevation view thereof;
FIG. 7 shows an enlarged rear elevation view thereof;
FIG. 8 shows a left side elevation view thereof;
FIG. 9 shows an enlarged left side elevation view thereof;
FIG. 10 shows a right side elevation view thereof;
FIG. 11 shows a top plan view thereof;
FIG. 12 shows an enlarged top plan view thereof;
FIG. 13 shows a bottom plan view thereof;
FIG. 14 shows an enlarged bottom plan view thereof;

FIG. 15 shows another top perspective view thereof, shown in use with additional exemplary environmental subject matter;

FIG. 16 shows another enlarged top perspective view thereof, shown in use with additional exemplary environmental subject matter;

FIG. 17 shows an exploded top perspective view thereof;
FIG. 18 shows an enlarged exploded top perspective view thereof;

FIG. 19 shows a top perspective view of a second embodiment of a container carrier showing our new design;

FIG. 20 shows an enlarged top perspective view thereof;

FIG. 21 shows a bottom perspective view thereof;

FIG. 22 shows an enlarged bottom perspective view thereof;

FIG. 23 shows a front elevation view thereof;

FIG. 24 shows a rear elevation view thereof;

FIG. 25 shows an enlarged rear elevation view thereof;

FIG. 26 shows a left side elevation view thereof;

FIG. 27 shows an enlarged left side elevation view thereof;

FIG. 28 shows a right side elevation view thereof;

FIG. 29 shows a top plan view thereof;

FIG. 30 shows an enlarged top plan view thereof;

FIG. 31 shows a bottom plan view thereof;

FIG. 32 shows an enlarged bottom plan view thereof;

FIG. 33 shows another top perspective view thereof, shown in use with additional exemplary environmental subject matter;

FIG. 34 shows another enlarged top perspective view thereof, shown in use with additional exemplary environmental subject matter;

FIG. 35 shows an exploded top perspective view thereof;

FIG. 36 shows an enlarged exploded top perspective view thereof;

FIG. 37 shows a top perspective view of a third embodiment of a container carrier showing our new design;

FIG. 38 shows an enlarged top perspective view thereof;

FIG. 39 shows a bottom perspective view thereof;

FIG. 40 shows an enlarged bottom perspective view thereof;

FIG. 41 shows a front elevation view thereof;

FIG. 42 shows a rear elevation view thereof;

FIG. 43 shows an enlarged rear elevation view thereof;

FIG. 44 shows a left side elevation view thereof;

FIG. 45 shows an enlarged left side elevation view thereof;

FIG. 46 shows a right side elevation view thereof;

FIG. 47 shows a top plan view thereof;

FIG. 48 shows an enlarged top plan view thereof;

FIG. 49 shows a bottom plan view thereof;

FIG. 50 shows an enlarged bottom plan view thereof;

FIG. 51 shows another top perspective view thereof, shown in use with additional exemplary environmental subject matter;

FIG. 52 shows another enlarged top perspective view thereof, shown in use with additional exemplary environmental subject matter;

FIG. 53 shows an exploded top perspective view thereof; and,

FIG. 54 shows an enlarged exploded top perspective view thereof.

The broken lines are shown for the purpose of illustrating both parts of the article as well as exemplary environmental subject matter. None of the broken lines form part of the

claimed design. The dot-dash broken lines represent the designation of enlargement views and form no part of the claimed design.
